SELF LOADING CONVEYER

Charles A. Young, Alamo, Colo., assignor to
 Alamo Coal Company, a corporation of
 Colorado

Application October 28, 1929, Serial No. 403,045

5 Claims. (Cl. 198—220)

This invention relates to reciprocating conveyers of the type in which a trough or other conduit is reciprocated with strokes of different lengths to effect an advancing movement of material from a point of supply at an end of the trough or conduit to a point of discharge at the opposite end of the same.

The rearward movement of the conveyer to the source of supply is accelerated with relation 10 to its forward movement toward the point of delivery so that the material fed onto the conveyer will be gradually advanced by the forward movement of the conveyer and by its own momentum and inertia during the more rapid 15 rearward movement of the same.

It is an object of the present invention to provide a conveyer of the above described character, transportably mounted upon a wheeled truck and thereby particularly adapted for use 20 in mines equipped with railways for the transportation of the excavated product.

Another object resides in the provision of a simple and highly efficient mechanism for the operation of the reciprocating element of the 25 machine and still other objects reside in the provision of certain adjustments adapting the machine for use under varying conditions, and in details of construction and novel and useful combinations and arrangements of parts as will 30 be fully explained in the course of the following description.

In the accompanying drawings in the several views of which like parts are similarly designated,

35 Figure 1 represents a partially broken plan view of the improved conveyer.

Figure 2, a side elevation of the machine, as shown in Figure 1,

Figure 3, an enlarged partially broken plan 40 view of the master section of the reciprocating element and the mechanism by which it is operated.

Figure 4, a partially sectional side elevation 45 of the machine as shown in Figure 3,

Figure 5, an enlarged cross section on the line 50 5—5, Figure 1, and

Figure 6, an enlarged cross section taken on the line 6—6, Figure 4.

55 Referring further to the drawings, the conveyer comprises a truck 5 the wheels 6 of which are flanged to move on a railway track 7.

The body of the truck is provided with boxes for the axles of the wheels and with suitable 55 bearings for the support of the gearing by which

a conveyer trough 8 supported for reciprocation on the truck, is operated.

An electric motor 9 mounted at an end of the truck body carries a grooved pulley 10, which transmits the movement of its rotor, to a similar 5 pulley 12 at the end of a jack shaft 13, through the medium of a plurality of belts 14.

A crank shaft 15 is provided with gear wheels 16 that mesh with pinions 17 on an intermediate shaft 18, and gear wheels 19 on the last mentioned shaft mesh with pinions 20 at the ends 10 of the before mentioned jack shaft.

The shaft 18 provides a support for a duplex rocker arm 21 which by means of a pitman 22 is operatively connected with the crank 23 of 15 the crank shaft 15.

Two parallel rods 24 connect the rocker arm 21 with the conveyer trough.

The arrangement of the crank and the rocker arm is such that by rotation of the crank shaft 20 in the direction of the arrow in Figure 4, a differential reciprocating movement is imparted to the trough, the forward movement in the direction of the point of discharge being slow and the return movement in the direction of 25 the arrow A in Figure 4, being comparatively rapid.

The rocker arm has a plurality of apertures 25 for the attachment of the connecting rods so that the ratio of the differential movements 30 of the conveyer trough may be varied within determinate limits.

The conveyer trough consists of a master section 26 directly mounted on the truck and a plurality of extension sections 27 which are connected to follow the reciprocating movement of the master section, imparted thereto by the motor through the intermediary of the hereinabove described transmission mechanism.

All of the sections are flat-bottomed with 40 flaring sides and outwardly projecting flanges at the upper edges of the sides.

The entire trough slants upwardly from its feed end for the purpose of discharging the material at an elevated point of delivery above 45 a pit car or other suitable receptacle, and the master section is with this end in view, slantingly supported on the wheeled truck.

Fastened to the body of the truck by two pairs of plates 44 are parallel slanting side 50 rails 28 on which are mounted a plurality of rollers 29 that are engaged by the flanges 30 of the master section of the trough.

A stiffening plate 31 fastened beneath the bottom of the master section engages the rollers 55

opposite to the flanges and thereby holds the section against upward displacement.

Both the flanges 30 and those provided by the plate 31 have strips 32 of wear-resisting metal 5 that engage the rollers.

Cross bars 33 fastened to the side rails of the truck body by means of their upwardly bent end portions 33a carry rollers 34 that hold the master section against lateral displacement by engagement with parallel angle bars 35 secured to the bottom of the section at opposite sides of the rollers.

The extension sections 27 at opposite ends of the master section are secured to each other 15 and to the master section by bolts or other suitable means.

The sections overlap one another at their ends and they are provided with outwardly projecting ears 36 for the application of the bolts which 20 fasten them together.

The section at the extreme end of the trough at which the material to be conveyed is fed into the trough, has a flat forwardly projecting shovel 37 that may enter into or beneath a 25 pile of the material by rearward movement of the trough, for the purpose of self-feeding.

The shovel may be provided with a plurality of fingers 33 to facilitate its entrance into the material.

30 It will be understood that the length of the conveyor may be varied according to different conditions by adding or removing the sections at opposite ends of the master section, but a more limited adjustment may be obtained by 35 providing two adjoining sections, preferably at the feed end of the trough, with lapping flanges which have a series of registering holes 39 for the reception of one or more bolts by which the sections are fastened together, all as shown in Figures 1 and 2 of the drawings.

40 It will be apparent that by these means the trough may be lengthened to a limited extent, which is of particular importance when it is desired to advance the shovel end of the trough 45 into the material at increasing distances from the truck.

The extensions at the feed end of the trough 50 may be supported on the ground, as shown, but at the upper or delivery end of the truck it is desirable to provide special means to relieve the master section of the weight of the extension sections.

55 The suspension devices shown in Figure 2 of the drawings, are of particular advantage when the machine is used in mine excavations having a comparatively low roof supported by the usual timbers, as shown at 40 in Figure 2.

The suspension means consist of chains 41 fastened to hooks or eyes in the roof timbers 60 and secured at their opposite ends to yokes 42 that extend beneath the trough sections cross-wise of the same.

65 The yokes, as best shown in Figure 5, may be made of hinged parts to facilitate their manipulation and application. They are shaped in conformity with the trough-like sections beneath which they are placed and they have outwardly projecting slotted ears 43 to admit a link of the chains.

70 It will be seen that the swinging support thus provided does not interfere with the reciprocating motion of the conveyor and permits of extending the conveyor to any desired length.

In the operation of the machine, the wheeled 75 truck is moved along the railway track to a po-

sition in workable proximity to the supply of material to be conveyed to pit cars placed on the rails forward of the truck.

The motor is connected in a convenient electric circuit and a differential reciprocating motion is imparted to the trough by the rotary movement of the crank shaft.

During the rearward motion of the trough the shovel at the lower end thereof is moved into the pile of material. During the subsequent 10 slow forward movement of the truck the material upon the trough is carried forwardly and during each subsequent quick return motion of the trough, the material either continues its 15 forward movement by its momentum or it remains in place by its inertia while the trough moves beneath the same.

In this manner the material is gradually advanced until at the upper end of the trough it falls into a pit car or other receptacle placed 20 beneath said end.

The machine is particularly adapted for use in coal mines to carry the mined coal to the pit cars by power-driven mechanical means.

The capacity of the machine may be increased 25 by manually supplying material to the reciprocating trough at the feed end of the same in addition to the material fed onto the trough, by the shovel.

Conveyors of the described type which are reciprocated at different velocities in opposite directions for the purpose of gradually advancing material from a point of supply to a distant point of discharge, are known in the art, and the present invention consists mainly in the 35 particular means for operating and constructing the conveyor as shown, and described, the means of adjustment and the method of adapting the machine for the particular purpose of mining coal and other products, as set forth in the 40 hereunto appended claims.

45 Distinctive features of the invention are that the conveyor may be readily transported from one part of a mine to another, that the extension sections are readily removed and replaced before and after the truck has been moved to a new point of operation, that the driving mechanism acts on but one trough section which actuates the entire conveyor, that the drive unit is the only part of the machine 50 requiring lubrication, and that the ratio of the differential movement of the conveyor may be varied according to the nature of the material to be conveyed.

55 It will be understood that if necessary any suitable means may be employed to lock the truck against movement on the railway track while the machine is in operation.

What I claim and desire to secure by Letters Patent is:

60 1. The combination with a trough-shaped conveyor, and suspension chains therefor, of yokes disposed beneath the conveyor and conforming to the outline thereof, each of the yokes comprising similar portions hingedly connected 65 at their inner ends and provided at their outer ends with offset slotted ears to detachably engage links of the suspension chains.

65 2. A transportable loader comprising a truck, a sectional conveyor-element adapted to convey 70 material from a feed-end adjacent the ground to an extension at an elevated point of delivery, suspension means for maintaining the extended portion of the conveyor in its elevated delivery position, said element including a master-section 75

- on the truck, and an extension of said section to the feed-end of the conveyer, the said suspension means being secured at a point above the top of the conveyer and connected thereto, 5
- 5 composed of relatively adjustable sections whereby the length of the feed-end and the elevated extension can be varied, motor driven mechanism on the truck to impart a differential reciprocating movement to the master-section, 10
- 10 and yokes disposed beneath the extended elevated delivery portion of the conveyer-element and conforming to the outline thereof, each of the yokes comprising similar portions hingedly connected at their inner ends and provided at 15
- 15 their outer ends with offset slotted ears to detachably engage the said suspension means. 15
3. A loader comprising a conveyer embodying middle, receiving and delivery sections, the receiving section being supported on the load susp- 20
- 20 taining surface, suspension means for the delivery section, the said suspension means being secured at a point above the top of the conveyer and connected thereto, and a portable support having the middle section slidably mounted 25
- 25 thereon, operating means on the portable support connected with the said middle section to impart a longitudinal reciprocatory movement to the conveyer to cause it to pick up the load and move it thereover, and yokes disposed be- 30
- 30 neath the delivery section of the conveyer and conforming to the outline thereof, each of the yokes comprising similar portions hingedly connected at their inner ends and provided at 35
- 35 their outer ends with offset slotted ears to detachably engage the said suspension means. 35
4. A loader comprising a support, a trough-shaped conveyer mounted thereon to recipro- 40
- 40 cate, means for movably suspending the conveyer at one end from a point above the top thereof, a train of gearing on the support including gear connected crank and intermediate
- shafts, a duplex rocker loosely mounted on the intermediate shaft, a pitman disposed intermediate the elements of the duplex rocker and connecting the latter to the crank portion of the crank shaft, pitmen at the sides of the 5
- 5 rocker connecting it to the conveyer to impart a slow movement thereto in the direction to pick up the load, and a quick reverse movement whereby to move the load continuously over the conveyer, driving means on the support for operating the train of gearing, and yokes disposed beneath the conveyer and conforming to the outline thereof, the said yokes being provided at their outer ends with means to detachably engage the said suspension means. 10
5. A loader comprising a support including parallel side rails, rollers at intervals in the length of the side rails, a conveyer trough between the side rails and provided with outer flanges engaging over the said rollers, means for 20
- 20 movably suspending the conveyer trough at one end from a point above the top thereof, a stiffening plate fastened to the bottom of the trough and extending beyond its sides and engaging under the aforesaid rollers to act jointly there- 25
- 25 with and with the outer flanges of the trough to retain the latter in place and direct it in its movements, cross bars at intervals in the length of the side rails having their end portions bent upwardly and attached to the said side rails, 30
- 30 rollers mounted centrally of the cross bars and spaced angle bars attached to the bottom of the trough and receiving the rollers therebetween mounted on the cross bars, and yokes disposed beneath the conveyer and conforming to the 35
- 35 outline thereof, each of the yokes comprising similar portions hingedly connected at their inner ends and provided at their outer ends with offset slotted ears to detachably engage the said suspension means. 40
